DESIGN FOR A VESTEE WITH DETACHABLE COLLAR

Anna Phillips, New York, N. Y.

Application July 19, 1941, Serial No. 192,315

Term of patent 7 years

To all whom it may concern:

Be it known that I, Anna Phillips, a citizen of the United States of America, residing in New York city, county of New York, and State of New York, have invented a new, original, and ornamental Design for a Vestee with Detachable Collar, of which the following is a specification, reference being had to the accompanying drawing, forming part thereof.

Fig. 1 is a front view of a vestee with detachable collar showing my new design.

Fig. 2 is a rear view thereof.

Fig. 3 is a front view of the vestee portion with the collar removed.

My design comprises a vestee having a V-necked front panel and a high necked rear panel stitched together at the shoulders and connected at the waistline by straps, in combination with a detachable collar of the specific configuration shown.

I claim:

The ornamental design for a vestee with detachable collar, substantially as shown and described.

ANNA PHILLIPS.
